UNITED STATES PATENT OFFICE.

MALTE J. MALLING, OF GRAND RAPIDS, MICHIGAN.

ELECTRIC APPLIANCE.

Application filed July 11, 1927. Serial No. 204,818.

This invention relates to an electrical appliance particularly designed as a combined plug and spool which may be used to make the electrical connection with a wall or floor 5 socket, and on which the cord which carries circuit wires leading to a lamp or other electrical device may be wound to a desired or necessary extent, whereby the cord between the plug and said appliance is held 10 straight and is neat and orderly in appearance where otherwise it would be tangled and disorderly, the length of the cord many times being considerably greater than the distance between the plug and the electric 15 device to which the cord leads. The construction which I have devised for this purpose is relatively simple, may be easily manufactured and the cord containing the circuit wires may be easily attached thereto. 20 And such combined plug and spool may be equipped for either direct connection to a wall socket or for connection to an intermediate plug which itself is directly connected with the wall or floor socket. 25 My invention consists in novel constructions and combinations and arrangements of parts for effectively attaining the ends stated, as will be apparent from the following description taken in connection with the accompanying drawing, in which,

Fig. 1 is an elevation of the outer end of the electrical appliance of my invention.

Fig. 2 is a side elevation thereof.

Fig. 3 is an elevation of the inner end of such appliance.

Fig. 4 is a side elevation taken at right angles to the side shown in Fig. 2.

Fig. 5 is a central section through the appliance substantially on the plane of line 5—5 of Fig. 1.

Fig. 6 is a central section through the inner member of the appliance modified for attachment to an auxiliary plug, and

Fig. 7 is an end elevation thereof.

Like reference characters refer to like parts in the different figures of the drawing.

In the construction, an inner member 1 of the spool and plug is made of suitable insulating material and preferably with an 50 outwardly extending beaded rim 2. Said member has a central opening 3 therethrough and at its inner side is formed with an integral annular ring 4, best shown in Fig. 5. The contact clips 5 which are designed for connection with the wall or floor 55 socket are equipped with screws 6 and have

the usual outwardly extending spaced apart prongs 7 which enter openings in the wall or floor socket. At the outer end of the member 1 there is formed a semi-cylindrical 60 groove 8 which leads to the opening 3 through said member.

The outer member 9 of the device is of similar form and likewise has a beaded rim 10 so that when the two members are placed together a spool is made having an annular concave recess entirely around the spool between said rims. The outer member 9 also has an opening 11 centrally through it considerably larger in diameter than the opening 3 in the first member. At one side the outer member 9 is radially slotted, as indicated at 12, from said central opening through the rim 10, and where the slot 12 joins with the opening 11 at the inner end of the member 9, said slot is somewhat widened and made into a groove 13 which joins with the groove 8 when the two members 1 and 9 are placed against each other for securing together. At the opposite side of the member 9 the rim 10 is slotted inwardly, as indicated at 14, and the slot terminates in an enlargement 15 of substantially circular form located in the body of the member 9 between the outer edge of the rim 10 and the inner 85 opening 11 (see Fig. 1).

The combined spool and plug is completed by securing the two parts 1 and 9 thereof together using connecting screws 16 for such purpose. The screws 16 pass through suitable openings in the outer member 9 thence through openings in the inner member 1 and thread at their ends through the clips 5 securely joining the two parts together. It is of course evident that the combined spool 95 and plug might be molded as a single piece but for facility of production it is better to make the two parts and secure them together so that when assembled they are in effect integral.

The cord 17 which contains the two wires of the circuit is passed through the openings 11 and 3 and the ends of the wire attached to the clips 5 in the usual manner by securing the same underneath the heads of the screws 6. The cord 17 may be then bent to one side and passed through the slot 12 until the substantially circular opening made by the two grooves 8 and 13 receive the cord. The cord may then be wound around the 110 spool into a coil 18, shown in Fig. 5, the end of the cord 19 passing upwardly through the

enlarged opening 15 at the inner end of the slot 14, it being evident that the cord may be passed through the slot 14 into the opening 15.

- 5 The construction described is very practical and with it any slack or excess in the length of a cord may be wound around the combined spool and plug with only so much of the cord extending between the device 10 when it is attached with a socket as is needed for the particular electrical appliance with which it is used. This eliminates disorderly and tangled cords.

Instead of providing the inner part or half 15 of the device with the contact clips, such part 1 may be modified so as to make a socket at its inner end frictionally engageable with the usual contact plug used many times with wall sockets. In Fig. 6 the part 20 1^a of the spool is equipped with the usual beaded rim 2^a and with the central opening 3 therethrough, and the annular ring 4^a is enlarged in diameter and extends farther from the rim 2^a than does the ring 4 from 25 the rim 2 in the first described construction. Within the ring 4^a a metal cup 20 is located secured in place by the connecting screws 16 which are used to fasten the two parts of the combined spool and plug together. The sides of the cup 20 are slit at 30 spaced apart points providing a plurality of spring fingers 21 which will act to grip against a plug 22 which may be inserted into the cup. The plug 22 has the usual terminal 35 prongs 7^a similar to the prongs 7 which insert into the openings of a floor or wall socket. This modification described is fully 40 capable of taking care of all of the slack or excess length in an electric cord as the excess may be wound around the spool with this form of appliance in the same manner as in that first described.

The invention is defined in the appended 45 claims and is to be considered comprehensive of all forms of structure coming within their scope.

I claim:

1. A device of the class described comprising, a body of suitable non-conducting material of substantially pulley-like shape, 50 said body having a central longitudinal opening therethrough, a second opening extending from the outer side of the body substantially midway between its ends to connect with said central opening and a 55 slot in one side and in the outer end portion of the body joining with said openings, a metallic contact member secured at the inner end of the plug with which an electric cord may have connection passing therefrom, through the central opening of said body, thence laterally through the second opening and thence wound around the body, its opposite end extending away from said body. 60

2. A construction containing the elements in combination defined in claim 1, said outer end portion of the body at a point a distance from said slot therein being slotted inwardly for a short distance and provided with an 70 enlarged opening at the inner end of the second slot through which the cord may pass away from said body.

3. A device of the class described comprising, a body of substantially pulley-like form 75 having an inner and an outer part of insulating material means joining said parts together to form a body having a deep annular groove therearound, said body having a central longitudinal opening therethrough, 80 metallic contact clips attached to the inner end of said body, and a cord connected to said clips and extending therefrom through the central opening in the body and thence laterally to the annular groove thereof, the 85 cord being adapted to be wound into a coil located in said groove, the outer end portion of the body being formed with a slotted passage through which the cord may pass from the central opening of the body to said 90 groove.

In testimony whereof I affix my signature.

MALTE J. MALLING.
